ATTORNEY

UNITED STATES PATENT OFFICE.

JACK H. HOWARD, OF TAYLOR, ARIZONA.

HORSE SHOE AND BOOT.

1,232,684.

Specification of Letters Patent. Patented July 10, 1917.

Application filed June 5, 1916. Serial No. 101,833.

To all whom it may concern:

Be it known that I, JACK H. HOWARD, a citizen of the United States, residing at Taylor, in the county of Navajo and State of 5 Arizona, have invented certain new and useful Improvements in Horse Shoes and Boots, of which the following is a specification.

This invention relates to an improved horseshoe and boot and the principal object of the invention is to provide an improved means for connecting the shoe with the boot so that the shoe may be releasably connected with the boot and thus when the shoe is worn out, the worn shoe removed 15 and a new one put in place.

Another object of the invention is to so construct the shoe and boot that the shoe will be securely connected with the boot and the boot which will be formed of leather 20 protected at its connection with the shoe so that it will not be cut by rock or by stamping.

Another object of the invention is to provide a boot which is so constructed that it 25 will be securely held in place.

This invention is illustrated in the accompanying drawings, wherein:—

Figure 1 is a view showing the boot applied to the horse's hoof.

30 Fig. 2 is a vertical sectional view through the improved shoe and boot.

Fig. 3 is a perspective view of a band for fitting upon the shoe.

Fig. 4 is a perspective view of the band 35 which fits upon the band shown in Fig. 3 and engaging the boot.

Fig. 5 is a perspective view of the boot, one portion of the same being broken away.

Fig. 6 is a perspective view of a wedge 40 serving to connect the shoe with the boot.

Fig. 7 is an enlarged sectional view through the toe portion of the shoe and boot.

This horseshoe 10 may be of any suitable 45 type and is provided with staples 11, one of which is positioned adjacent the toe of the shoe and one of which is positioned adjacent each heel. The metal band 12 which conforms to the contour of the shoe 10 fits 50 upon this shoe and is provided with openings 13 through which the staples 11 will pass thus preventing movement of the band upon the shoe when in place. The boot 14 which is preferably formed of leather fits 55 upon the collar 15 within the flange 16 there-

of and is provided with an inturned flange 17 which is provided with openings registering with the openings 18 of the collar 15 so that the staples 11 can pass through the collar 15 and through the flange 17 of the 60 leather shoe. Therefore when the horse-shoe 10, band 12, collar 15 and boot 14 are in place and the wedges 19 passed through the staples 11 with the staples fitting into the grooves or seats 20, these various parts 65 will be very rigidly connected thus providing a substantially solid structure which will be strong and durable and not liable to easily come apart. The horse's hoof is placed within the boot 14 and after the 70 straps have been connected through the medium of the buckle 23, the horse shoe will be releasably connected with the horse's hoof. After the horse shoe 10 has worn out, the straps 21 and 22 can be released thus permitting the boot to be removed from the horse's hoof. The wedges 19 can then be 75 easily withdrawn from the staples thus releasing the shoe 10 and permitting a new shoe to be put in place or any necessary 80 repairs made to the shoe in case its use is to be continued.

I have therefore provided a horseshoe and hoof engaging boot, so constructed that the shoe can be securely connected with the boot 85 and the boot releasably held about the hoof. I have further provided a protection for the lower portion of the boot so that it will not be cut by stones or rough places in the road or by the horse stamping. 90

What is claimed is:—

1. A horseshoe, staples carried by said horseshoe, a band resting upon said horseshoe and provided with openings through which said staples pass, a collar resting upon 95 said band and provided with openings through which said staples pass, said collar being provided with an outer upwardly extending flange, a boot formed of flexible material fitting within the flange of said 100 collar and provided with an inwardly extending flange having openings through which said staples pass, securing means passing through said staples to hold the same in place, and means carried by said boot 105 for holding the same about the hoof of an animal.

2. A horseshoe, a plate resting upon said shoe, a collar resting upon said plate and provided with an external flange, a boot fit- 110

ting within the flange of said collar and provided with an inwardly extending flange resting upon said collar, securing means carried by said shoe and passing through 5 said plate and collar and through the flange of said boot, and means for engaging said fastening means to hold the same in place.

3. A shoe, a collar positioned above said shoe and provided with an upwardly extending external flange, a boot fitting within the flange of said collar and provided with an inwardly extending flange resting upon the collar, fastening means for said shoe passing through the collar and flange of 15 said boot, and means carried by said boot

for holding the same about the hoof of an animal.

4. A shoe, a collar positioned above said shoe, a boot having its lower portion resting upon said collar and protected by the same, 20 securing means extending from said shoe through said collar and boot, and means carried by said boot for securing the boot about the hoof of an animal.

In testimony whereof I affix my signature 25 in presence of two witnesses.

JACK H. HOWARD.
